UNITED STATES PATENT OFFICE.

CARL O. ANDERSON, OF MITCHELL, SOUTH DAKOTA.

VALVE-ADJUSTING TOOL.

Application filed December 1, 1927. Serial No. 237,111.

This invention relates to valve adjusting tools and it consists in the novel features hereinafter described and claimed.

Ordinarily, it is difficult to prevent a slight movement of the adjusting screw of a valve mechanism when the lock nut is being tightened thereon, and it is an object of the present invention to provide means for securely holding the adjusting screw at the proper position when the lock nut is being tightened thereon, without altering the adjustment of the valve assembly due to a tendency of the adjusting screw to turn with the lock nut while the nut is being tightened.

With this object in view, the tool includes a frame having angularly disposed end portions, one of which is provided with spaced lugs adapted to straddle the rocker arm of the valve mechanism. The other end portion of the frame is provided with an opening which receives the shaft of a screw driver. The last mentioned end portion of the frame is further provided adjacent said opening with a recess in which a cam lever is fulcrumed. A collar is applied to the shaft of the screw driver and the end of the frame having the opening rests upon the said collar. When in use, the working end of the screw driver shaft is inserted in the slot of the adjusting screw of the valve mechanism, and by turning the screw driver in the opening of the frame, the said screw is adjusted. When the screw is properly adjusted, the lever is swung whereby the cam end thereof engages the side of the shaft of the screw driver and fixes the shaft with relation to the frame. Thus, the screw is held at the adjusted position and when the lock nut is tightened upon the screw, the screw is fixed at the adjusted position upon the rocker arm of the valve mechanism.

In the accompanying drawings:

Figure 1 is a side elevational view of the valve adjusting tool, showing the same applied.

Figure 2 is an edge elevational view of the tool showing part of the valve mechanism in section and cut upon the line 2—2 of Figure 1.

Figure 3 is a horizontal sectional view of the tool cut on the line 3—3 of Figure 1.

The valve mechanism, upon which the tool is used, includes a rocker arm 1 of conventional form, having an adjusting screw 2 threaded therein, and a lock nut 3 thread-

ed upon the screw and adapted to bind against the surface of the rocker arm when tightened.

The valve adjusting tool comprises a frame 4 provided with angularly disposed end portions, one of which is provided with spaced lugs 5 adapted to straddle the intermediate portion of the rocker arm 1, when the tool is applied thereto. The frame 4 is provided at its opposite end portion with an opening 6 adapted to receive the shaft 7 of a screw driver 8. A collar 9 is mounted upon the intermediate portion of the shaft 7 of the screw driver and is held at a desired point thereon by means of a set screw 10. The frame 4 is further provided with a recess 11 which communicates at one end with the opening 6. A cam lever 12 has its working end disposed in the said recess and the said lever is pivotally connected with the frame at a point adjacent the opening 6 and when the lever 12 is swung, its cam end may enter the recess 6 and impinge against the side of the screw driver shaft 7 whereby the said screw driver shaft is held against rotation in the opening 6.

When being used, the lugs 5 are placed in position at the opposite sides of the intermediate portion of the rocker arm 1 and that end portion of the frame 4 which is provided with the recess is disposed approximately parallel with the rocker arm. The working end of the screw driver shaft 7 is inserted in the slot of the screw 2 and the screw driver 8 is rotated so that the screw 2 is adjusted to the desired position in the rocker arm.

After the screw 2 has been adjusted to the desired position, pressure is applied to the upper end of the lever 12 whereby said lever is swung and its cam end engages the side of the screw driver shaft 7. At the same time, the recess end of the frame is forced down upon the upper surface of the collar 9. Thus, the screw 2 is held against turning movement and while the said screw is being thus confined, the nut 3 may be tightened so that inner surface binds against the surface of the rocker arm 1 and the screw 2 is secured or locked at the adjusting position, and without disturbing the adjustment.

Therefore, it will be seen that an adjusting tool of simple and durable structure is provided and that the same may be easily and conveniently used for assuring that the

screw of the valve mechanism is held at the proper position when it is being locked or secured with relation to the rocker arm of the valve mechanism.

- 5 From the foregoing description of the construction of my improved apparatus, it will be seen that I have provided a simple, inexpensive and efficient means for carrying out the objects of my invention and while 10 I have particularly described the elements best adapted to perform the functions set forth, it is obvious that various changes in form, proportion and in the minor details of construction may be resorted to without 15 departing from the spirit or sacrificing any of the principles of the invention.

Having described my invention, what is claimed is:

1. A valve adjusting tool comprising a 20 frame having angularly disposed end portions one of which is provided with spaced lugs, the other end portion having an opening, a screw driver shaft received in said opening, a collar mounted upon the shaft 25 and engaging the frame, and a cam lever pivoted upon the frame and having a working end adapted to impinge the screw driver shaft.
2. A valve adjusting tool comprising a 30 frame provided with angularly disposed end portions, one end portion having means for engaging the rocker arm of a valve mechanism, the other end portion having an opening and a recess communicating therewith, 35 a screw driver shaft received in said opening, a cam lever pivoted to the arm and entering said recess and having a working

end adapted to impinge the screw driver shaft.

3. A valve adjusting tool comprising a 40 frame having means for engaging the valve mechanism and provided with an opening, a screw driver shaft received in said opening, a collar carried by the shaft and engaging the frame, and a cam lever pivoted upon 45 the frame and having a working end adapted to engage the screw driver shaft.

4. A valve adjusting tool comprising a 50 frame having means adapted to engage the valve mechanism, said frame having an opening and a recess communicating therewith, a screw driver shaft received in the opening, a collar carried by the screw driver shaft and engaging the frame, a cam lever received in the recesses of the frame and 55 pivoted thereto and having a working end adapted to impinge the screw driver shaft.

5. A valve adjusting tool comprising a 60 frame having angularly disposed end portions, one of which is provided with spaced 65 lugs adapted to straddle a portion of the valve mechanism, the other end portion of the frame having an opening and a recess communicating at one end therewith, a screw driver shaft received in said opening, a collar adjustably mounted upon the screw driver shaft and adapted to engage the frame, and a cam lever having its cam end 70 received in the recess, said lever being pivoted to the frame and the working end of the lever adapted to impinge the screw driver shaft held in the opening.

In testimony whereof I affix my signature.
CARL O. ANDERSON.
